YARN-ADVANCING REEL

Alvin L. Ewing, Richmond, Va., assignor to E. I. du Pont de Nemours & Company, Wilmington, Del., a corporation of Delaware

Application January 10, 1946, Serial No. 640,231

13 Claims. (Cl. 28—71.6)

1

This invention relates to yarn-advancing apparatus, and more particularly to a yarn-advancing reel in which yarn is continuously and progressively advanced in the form of a helix.

An object of this invention is to provide a new and improved yarn-advancing reel for continuously advancing yarn in the form of a helix.

Another object of this invention is to provide a yarn-advancing reel of a relatively simple construction and having relatively few moving parts.

A further object of this invention relates to a yarn-advancing apparatus which can be readily removed and replaced in a machine.

Other and additional objects will appear hereinafter.

The objects of this invention are accomplished, in general, by winding yarn in the form of a helix onto a reel having two sets of yarn-supporting bars rotating with the reel, the bars of one set being fixed with respect to axial and radial movement and disposed alternately between the bars of the other set which are movable radially and axially of the reel, and imparting radial in-and-out motion and axial reciprocation to the movable bars whereby the yarn is continuously and smoothly advanced along its length, the radial in-and-out movement and axial reciprocation of the movable bars being accomplished by a cam mechanism.

In one embodiment, the movable and fixed bars are so positioned that normally a yarn wrapped around the reel contacts the fixed bars in a zone constituting approximately one-half of the reel while resting on the movable bars in a zone constituting approximately the other half of the reel. By a cam mechanism, the movable bars are caused to successively recede radially on approximately half of the reel and expand radially on approximately the other half of the reel. The cam surfaces are so shaped that at the point where the fixed and movable bars are in neutral position, i. e. same radial distance from the reel axis, there is no axial movement of the movable bars, but as the movable bars are successively retracted radially from this point the cam causes them to move axially in the direction opposite to the direction of travel of the yarn over the reel. This axial movement continues until the movable bars again reach the neutral position on the opposite side of the reel. The bars then successively move radially outwardly to contact and carry the yarn free from the fixed bars and also successively move axially in the direction of the yarn advancement to advance the yarn in one direction until the yarn is again transferred, by

2

radially receding the movable bars, onto the fixed bars at the neutral position. By repetition of the cycle, the yarn is continuously advanced in a helix over the reel.

5 The present invention will be more easily understood by reference to the following detailed description when taken in connection with the accompanying drawings, in which:

Figure 1 is a longitudinal vertical section of a yarn-advancing reel taken along lines 1—1 of Figure 3, constructed in accordance with the invention;

Figure 2 is a section taken on the line 2—2 of Figure 1;

15 Figure 3 is a section taken on the line 3—3 of Figure 1; and

Figure 4 is a section taken on the line 4—4 of Figure 1.

Referring to the drawings, wherein like reference numerals designate like parts, the reference numeral 10 designates the main shaft of the reel and is rotatably supported adjacent its ends in outboard bearings 12 and 14 appropriately mounted in the machine. An end plate 16 positioned on a sleeve 18 is secured to shaft 10 by means of set screw 20. An end plate 22, disposed in spaced relationship to end plate 16, is secured to sleeve 24 by set screw 26, the sleeve 24 being rotatably mounted with respect to shaft 10, as will hereinafter become apparent.

A set of yarn-supporting bars 30, arranged circumferentially and in spaced relationship, are fixedly secured to end plates 16 and 22. In the form shown, each fixed bar 30 extends longitudinally of the reel and is parallel to the major axis of the reel.

The drives for shaft 10 and end plate 22 are, by equal gears, meshed into one common drive gear so that there will be no distortion of the assembly. In the form shown in Figure 1, a gear 34, secured to shaft 36, driven from any suitable source such as from motor R through gears S and T, drives gear 38 which is secured by set screw 40 to shaft 10 whereby rotary motion is imparted to shaft 10. Since end plate 16 is secured to shaft 10, it will rotate therewith. End plate 22 is provided with gear 44 which is driven by gear 46 also carried on shaft 36.

A set of movable bars 50 are positioned in alternate spaced relationship with respect to the fixed bars 30. Each bar 50 is carried at the top of an individual separate web member 52, the opposite ends of which are mounted for radial and axial movement, obtained as hereinafter explained, in fixed paths relative to the adjacent fixed bars in

slots 54 and 56 in end plates 16 and 22 respectively.

Each web member 52 is provided on the bottom thereof, adjacent each side, with a pair of cam followers 60 and 62. Cam follower 60 cooperates with cam 64, and cam follower 62 cooperates with cam 66. In the form shown, cams 64 and 66 are formed of two pieces and the combined cam is designated generally by the reference numeral 68.

Cam mechanism 68 are secured to sleeve 70 by set screws 72. A gear 74 fixedly mounted on shaft 76, which is driven in any suitable manner as, for instance, through gears 107, 105, 106 from shaft V of motor R and cooperates with gear 78 secured to sleeve 70 by means of key U shown in Figure 1. It is thus apparent that upon rotation of sleeve 70, which is in a direction opposite to that of main shaft 10, cam mechanisms 68 will be rotated in a direction opposite to that of the reel.

Each of cams 64 is of a design so that upon rotation each web member 52 will be reciprocated axially whereby a similar movement will be given to bar 50 carried by such web member. Each of cams 66 is of a design which upon rotation will impart to each web member 52, and hence to movable bar 50 carried thereby, a radial in-and-out movement.

From the description thus far, it is apparent that, upon rotation of the reel, bars 30 will be moved in a circular path about the main reel shaft 10 but will be fixed with respect to any radial or axial movement thereof, while bars 50 will be movable not only in a circular path about the main reel shaft 10 but also radially inwardly and outwardly as well as axially relative to the main reel shaft 10.

Due to the respective movement, bars 30 are herein called "fixed bars" while bars 50 are called "movable bars."

In order to support the movable bars 50 against deflection due to tension set up by the yarn wraps around the reel as well as to maintain rigidity of the bars, each web member 52 is provided at approximately the center of the bottom thereof with a follower 80 which cooperates with eccentric 82 secured to sleeve 70 by set screw 84. The eccentricity of eccentric 82 corresponds to the shape of cam 66 and together therewith controls the radial movement of bars 50. The fixed bars 30 are supported intermediate the length thereof by circular ring 85 which allows free movement of movable bars 50.

In the form shown in Figures 2 and 3, the yarn-contacting surfaces of fixed bars 30 and movable bars 50 are of the same cross-section. The yarn-contacting portion of each of the bars, in the form shown, consists of two spaced semi-cylindrical projections 90 extending longitudinally of the respective member at the front and rear edges thereof.

The driving mechanism is enclosed in a housing, generally designated by the reference numeral 94. A cylindrical diaphragm 96 is positioned on shoulders 98 and 100 of end plates 16 and 22 respectively. Securing rings 102 and 104 cooperating with shoulders 98 and 100 respectively secure diaphragm 96 in position.

In operation, shaft 10 is rotated in a direction opposite to sleeve 70 and end plates 16 and 22 are rotated at a faster speed than cam mechanisms 68 and eccentric 82, which rotate in the direction opposite to that of the end plates. The yarn is wrapped around the reel in a helix. Due

to the mode of mounting the assemblies for movable bars 50 hereinbefore described, when a yarn is wrapped around the reel it contacts the fixed bars 30 in approximately one-half of the reel while resting on the movable bars 50 in approximately the other half of the reel. As shown in Figure 2, the yarn rests on the movable bars 50 in the zone designated by the reference character A and is in contact with the fixed bars 30 in zone B. The zone designated by the reference character B. The yarn is also in contact with both the fixed and movable bars in the zones designated by the reference characters C and D hereinafter called "neutral zones." In other words, the movable bars 50 are in the radially expanded position in zone A and in the radially receded position in zone B. During operation, due to the cooperation of cams 66 with cam followers 62 and eccentric 82 with follower 80, movable bars 50 are caused to move from the radially expanded position in zone A to the radially receded position in zone B. The movable bars 50, in passing from zone A to zone B, pass through neutral zone C wherein movable bars 50 are the same radial distance from the reel axis as fixed bars 30, and both bars carry the yarn. The slope of cams 64, which controls the axial movement of movable bars 50, is such that, when the fixed and movable bars are the same radial distance from the center 30 of the axis as in zone C, the movable bars are not moved axially. However, as the bars pass from neutral zone C to zone B and movable members 50 recede radially, cam 64 is of such shape as to cause movable bars 50 to move axially in a direction opposite to the travel of the yarn over the reel. Upon leaving zone B, the fixed and movable bars move into neutral zone D where the fixed and movable bars are the same distance from the axis and wherein the movable bars are not moved axially. However, as soon as the bars move out of neutral zone D into zone A, movable bars 50 are moved radially outwardly to contact the yarn free of the fixed bars, at which time the movable bars are moved axially in the direction of feed of the yarn travel. The cycle of operation is continuously repeated.

In the instant reel, as the movable bars move radially outwardly to the greater diameter of the reel, the distance between each movable bar increases slightly and, vice versa, decreases as they return to the neutral position on the opposite side. In such radial movements the movable bars, however, do not move in an angular direction relative to the adjacent fixed bars. This action more evenly distributes the tension, prevents any concentrated tension differences at the neutral points, and reduces the possibility of slippage of the yarn on the bars at these points.

The relative rate of rotation between the cams and the reel determines the advancement cycles per revolution of the reel which, in turn, controls the increment of yarn advancement. Though the cams controlling the movable bars were hereinbefore described as rotating in a direction opposite to the yarn advancement, it is to be understood that the cams can be rotated in either direction or remain stationary. When the cams revolve in the same direction as the reel, the yarn advancement increment is smaller than that obtained when the cams rotate in a direction opposite to the rotation of the reel. When the cams are stationary, the yarn advancement increment is fixed to that of the pitch of the cams. Thus, by appropriate relative rates of rotation, any desired advancement increment can be obtained.

When the reel is tapered, it is particularly desirable to have the advancement increment as small as possible to prevent tension differences in the yarn wraps.

In the embodiment described, the yarn-carrying surfaces of the bars were parallel to the axis of the reel. The invention is not restricted thereto since the bars may be tapered to increase or decrease the tension on the yarn as it advances along the reel.

As is apparent from the description, the reel is so constructed that by the removal of the outboard bearing 12 and the loosening of set screw 20, the entire reel assembly can be slipped off shaft 10 and a replaceable reel slipped on. This is of obvious advantage especially when repairs have to be made.

The yarn-advancing reel herein described can be used for the advancement of yarn alone or while it is being processed by appropriate treating fluids.

The yarn-bearing surface is made of a material which does not deleteriously affect the yarn and is inert to the yarn-processing liquids if used. It can be made of various materials, such as ceramics, stainless steel, nickel alloys containing a high proportion of nickel, such as those sold by Haynes Stellite Company under the name Hastelloy, etc., depending on the reaction of the processing fluids if used.

The diaphragm 96 serves to seal off the inner part of the reel, and the housing 94 similarly serves for the drive mechanism. By the use of diaphragm 96, the wearing parts can be constructed of suitably wearing materials which are or are not corrosive-resistant. The portion of the apparatus extending outwardly beyond the diaphragm 96 is made of non-corrosive material.

The reel is intended to be used preferably when shaft 10 is in a horizontal position. It can be supported at both ends or at one end by a cantilever support.

The present invention provides a simple, inexpensive and easy-to-operate yarn-advancing apparatus which is characterized by relatively few moving parts, access to which can be readily had for the purpose of repairs when necessary.

Since it is obvious that many changes and modifications can be made in the above-described details without departing from the nature and spirit of the invention, it is to be understood that the invention is not to be limited thereto except as set forth in the appended claims.

I claim:

1. A yarn-advancing mechanism comprising a reel having a central reel shaft, means for rotating said reel shaft, two sets of yarn-contacting bars mounted to rotate about the center axis of said shaft, one of said sets of yarn-contacting bars being disposed alternately between the yarn-contacting bars of the other set, means fixedly mounting one of said sets of yarn-contacting bars against radial and axial movement, means mounting the yarn-contacting bars of the other of said sets for axial reciprocation and radial in-and-out movement from the center of the reel in a fixed path wherein each movable yarn-contacting bar remains the same distance in an angular direction relative to the adjacent fixed yarn-contacting bars, means operative during rotation of the reel to move successively the movable yarn-contacting bars in said fixed path from radially expanded position, where they contact the yarn, to radially receded position where they are out of contact with the yarn, and means to move the movable

yarn-contacting bars, while in radially expanded position, axially in the direction of the yarn travel over the reel and in the opposite direction while in the radially receded position, but impart no axial movement to said movable bars when the latter and the fixed bars are the same radial distance from the reel axis.

2. A yarn-advancing mechanism comprising a reel having a central reel shaft, means for rotating said reel shaft, two sets of yarn-contacting bars mounted to rotate about the center axis of said shaft, one of said sets of yarn-contacting bars being disposed alternately between the yarn-contacting bars of the other set, means fixedly mounting one of said sets of yarn-contacting bars against radial and axial movement, means mounting the yarn-contacting bars of the other of said sets for axial reciprocation and radial in-and-out movement from the center of the reel in a fixed path wherein each movable yarn-contacting bar remains the same distance in an angular direction relative to the adjacent fixed yarn-contacting bars, cam means operative during rotation of the reel to move successively the movable yarn-contacting bars in said fixed path from radially expanded position, where they contact the yarn, to radially receded position where they are out of contact with the yarn, and cam means to move the movable yarn-contacting bars, while in radially expanded position, axially in the direction of the yarn travel over the reel and in the opposite direction while in the radially receded position, the last named cam means imparting no axial movement to said movable bars when said movable bars and the fixed bars are the same radial distance from the reel axis.

3. A yarn-advancing mechanism comprising a reel having a central reel shaft, means for rotating said reel shaft, two sets of yarn-contacting bars mounted to rotate about the center axis of said shaft, one of said sets of yarn-contacting bars being disposed alternately between the yarn-contacting bars of the other set, means fixedly mounting one of said sets of yarn-contacting bars against radial and axial movement, means to eccentrically mount the other set of yarn-contacting bars relative to said reel shaft for radial in-and-out movement from the center of the reel in a fixed path wherein each movable yarn-contacting bar remains the same distance in an angular direction relative to the adjacent fixed yarn-contacting bars whereby normally said bars in a zone constituting approximately one-half of the periphery of the reel are in radially expanded position and in a zone constituting approximately the other half of the periphery of the reel are in radially receded position, said eccentrically mounted bars, during rotation of the reel, moving successively in said fixed path from radially expanded position, where they contact the yarn, to radially receded position where they are out of contact with the yarn, and means to move the eccentrically mounted yarn-contacting bars, while in radially expanded position, axially in the direction of the yarn travel over the reel and in the opposite direction while in the radially receded position.

4. A yarn-advancing mechanism comprising a reel having a central reel shaft, means for rotating said reel shaft, two sets of yarn-contacting bars mounted to rotate about the center axis of said shaft, one of said sets of yarn-contacting bars being disposed alternately between the yarn-contacting bars of the other set, means

fixedly mounting one of said sets of yarn-contacting bars against radial and axial movement, means mounting the yarn-contacting bars of the other of said sets for axial reciprocation and radial in-and-out movement from the center of the reel in a fixed path wherein each movable yarn-contacting bar remains the same distance in an angular direction relative to the adjacent fixed yarn-contacting bars, said means normally positioning the movable yarn-contacting bars in radially expanded position in a zone constituting approximately one-half of the periphery of the reel and in radially receded position in a zone constituting approximately the other half of the periphery of said reel, means operative during rotation of the reel to move successively the movable yarn-contacting bars in said fixed path from radially expanded position where they contact the yarn to radially receded position where they are out of contact with the yarn, and means to move the movable yarn-contacting bars, while in radially expanded position, axially in the direction of the yarn travel over the reel and in the opposite direction while in the radially receded position but impart no axial movement to said movable bars when the latter and the fixed bars are the same radial distance from the reel axis.

5. A yarn-advancing mechanism comprising a reel having a central reel shaft, means for rotating said reel shaft, two sets of yarn-contacting bars mounted to rotate about the center axis of said shaft, one of said sets of yarn-contacting bars being disposed alternately between the yarn-contacting bars of the other set, means fixedly mounting one of said sets of yarn-contacting bars against radial and axial movement, means mounting the yarn-contacting bars of the other of said sets for axial reciprocation and radial in-and-out movement from the center of the reel in a fixed path wherein each movable yarn-contacting bar remains the same distance in an angular direction relative to the adjacent fixed yarn-contacting bars, said means normally positioning the movable yarn-contacting bars in radially expanded position in a zone constituting approximately one-half of the periphery of the reel and in radially receded position in a zone constituting approximately the other half of the periphery of said reel, cam means operative during rotation of the reel to move successively the movable yarn-contacting bars in said fixed path from radially expanded position where they contact the yarn to radially receded position where they are out of contact with the yarn, and cam means to move the movable yarn-contacting bars, while in radially expanded position, axially in the direction of the yarn travel over the reel and in the opposite direction while in the radially receded position, the last named cam means imparting no axial movement to said movable bars when said movable bars and the fixed bars are the same radial distance from the reel axis.

6. A yarn-advancing mechanism comprising a reel having a central shaft, means for rotating said reel shaft, a pair of spaced end plates, one of said end plates being secured to said reel shaft, means to separately rotate the other of said end plates during rotation of said reel shaft, a set of spaced circumferentially arranged yarn-contacting bars secured to said end plates, a second set of yarn-contacting bars disposed alternately between the yarn-contacting bars of the first set, each yarn-contacting bar of the second set being

secured to a respective web member, means to rotate said web member during rotation of said reel shaft, means mounting the web members for axial reciprocation and radial in-and-out movement in a fixed path relative to the adjacent fixed yarn-contacting bars, means operative during rotation of the web members about said reel shaft to successively move said web members in said fixed path from radially expanded position, where the yarn-contacting bars carried thereby are in yarn-contacting position, to radially receded position where said yarn-contacting bars are out of yarn-contacting position, and means to move the web members supporting the yarn-contacting bars in radially expanded position axially in the direction of the yarn travel over the reel and in the opposite direction while in the radially receded position, but impart no axial movement to the web members when the bars carried thereby are the same radial distance from the reel axis as the fixed bars.

7. A yarn-advancing mechanism comprising a reel having a central shaft, means for rotating said reel shaft, a pair of spaced end plates, one of said end plates being secured to said reel shaft, means to separately rotate the other of said end plates during rotation of said reel shaft, a set of spaced circumferentially arranged yarn-contacting bars secured to said end plates, a second set of yarn-contacting bars disposed alternately between the yarn-contacting bars of the first set, each yarn-contacting bar of the second set being secured to a respective web member adapted to move in a fixed path relative to the adjacent fixed yarn-contacting bars, means to rotate said web member during rotation of said reel shaft, means eccentrically mounting the web members whereby during rotation of the web members about said reel shaft said web members successively move in a fixed path relative to the adjacent fixed yarn-contacting bars from expanded position, where the yarn-contacting bars carried thereby are in yarn-contacting position, to radially receded position where said yarn-contacting bars are out of yarn-contacting position, and means to move the web members supporting the yarn-contacting bars in radially expanded position axially in the direction of the yarn travel over the reel and in the opposite direction while in the radially receded position, but impart no axial movement to the web members when the bars carried thereby are the same radial distance from the reel axis as the fixed bars.

8. A yarn-advancing mechanism comprising a reel having a central shaft, means for rotating said reel shaft, a pair of spaced end plates, one of said end plates being secured to said reel shaft, means to separately rotate the other of said end plates during rotation of said reel shaft, a set of spaced circumferentially arranged yarn-contacting bars secured to said end plates, a second set of yarn-contacting bars disposed alternately between the yarn-contacting bars of the first set, each yarn-contacting bar of the second set being secured to a respective web member adapted to move in a fixed path relative to the adjacent fixed yarn-contacting bars, means to rotate said web member during rotation of said reel shaft, means eccentrically mounting the web members to normally position the yarn-contacting members carried thereby in a zone constituting one-half of the periphery of the reel in radially expanded position and the yarn-contacting bars carried thereby in a zone constituting approxi-

imately the other half of the periphery of the reel in radially receded position whereby during rotation of the web members about said reel shaft the respective yarn-contacting bars will successively move in a fixed path relative to the adjacent fixed yarn-contacting bars from radially expanded position, where the yarn-contacting bars carried by said web members are in yarn-contacting position, to radially receded position where said yarn-contacting bars are out of yarn-contacting position, and means to move the web members supporting the yarn-contacting bars in radially expanded position axially in the direction of the yarn travel over the reel and in the opposite direction while in the radially receded position, but impart no axial movement to the web members when the bars carried thereby are the same radial distance from the reel axis as the fixed bars.

9. A yarn-advancing mechanism comprising a reel having a central shaft, means for rotating said reel shaft, a pair of spaced end plates, one of said end plates being secured to said reel shaft, means to separately rotate the other of said end plates during rotation of said reel shaft, a set of spaced circumferentially arranged yarn-contacting bars secured to said end plates, a second set of yarn-contacting bars disposed alternately between the yarn-contacting bars of the first set, each yarn-contacting bar of the second set being secured to a respective web member adapted to move in a fixed path relative to the adjacent fixed yarn-contacting bars, means to rotate said web member during rotation of said reel shaft, means eccentrically mounting the web members to normally position the yarn-contacting members carried thereby in a zone constituting one-half of the periphery of the reel in radially expanded position and the yarn-contacting bars carried thereby in a zone constituting approximately the other half of the periphery of the reel in radially receded position whereby during rotation of the web members about said reel shaft the respective yarn-contacting bars will successively move in a fixed path relative to the adjacent fixed yarn-contacting bars from radially expanded position, where the yarn-contacting bars carried by said web members are in yarn-contacting position, to radially receded position where said yarn-contacting bars are out of yarn-contacting position, and cam means to move the web members supporting the yarn-contacting bars in radially expanded position axially in the direction of the yarn travel over the reel and in the opposite direction while in the radially receded position, but impart no axial movement to the web members when the bars carried thereby are the same radial distance from the reel axis as the fixed bars.

10. A yarn-advancing mechanism comprising a reel having a central shaft, means for rotating said reel shaft, a pair of spaced end plates, one of said end plates being secured to said reel shaft, means to separately rotate the other of said end plates during rotation of said reel shaft, a set of spaced circumferentially arranged yarn-contacting bars secured to said end plates, a second set of yarn-contacting bars disposed alternately between the yarn-contacting bars of the first set, each yarn-contacting bar of the second set being secured to a respective web member adapted to move in a fixed path relative to the adjacent fixed yarn-contacting bars, means to rotate said web member during rotation of said reel shaft, means eccentrically mounting the web members

5 to normally position the yarn-contacting members carried thereby in a zone constituting one-half of the periphery of the reel in radially expanded position and the yarn-contacting bars carried thereby in a zone constituting approximately the other half of the periphery of the reel in radially receded position whereby during rotation of the web members about said reel shaft the respective yarn-contacting bars will successively move in a fixed path relative to the adjacent fixed yarn-contacting bars from radially expanded position, where the yarn-contacting bars carried by said web members are in yarn-contacting position, to radially receded position 10 where said yarn-contacting bars are out of yarn-contacting position, cam means to move the web members supporting the yarn-contacting bars in radially expanded position axially in the direction of the yarn travel over the reel and in the opposite direction while in the radially receded position, but impart no axial movement to the web members when the bars carried thereby are the same radial distance from the reel axis as the fixed bars, and means to rotate said cam means in the direction opposite to that of said reel shaft.

11

mately the other half of the periphery of the reel in radially receded position whereby during rotation of the web members about said reel shaft the respective yarn-contacting bars will successively move in a fixed path relative to the adjacent fixed yarn-contacting bars from radially expanded position, where the yarn-contacting bars carried by said web members are in yarn-contacting position, to radially receded position where said yarn-contacting bars are out of yarn-contacting position, cam means to move the web members supporting the yarn-contacting bars in radially expanded position axially in the direction of the yarn travel over the reel and in the opposite direction while in the radially receded position, but impart no axial movement to the web members when the bars carried thereby are the same radial distance from the reel axis as the fixed bars, means to rotate said cam means in the direction opposite to that of said reel shaft, and means to prevent deflection of said movable bars due to the tension set up by the yarn wraps around the reel.

13. A yarn-advancing mechanism comprising a reel having a central shaft, means for rotating said reel shaft, a pair of spaced end plates, one of said end plates being secured to said reel shaft, means to separately rotate the other of said end plates during rotation of said reel shaft, a set of spaced circumferentially arranged yarn-contacting bars secured to said end plates, a second set of yarn-contacting bars disposed alternately between the yarn-contacting bars of the first set, each yarn-contacting bar of the second set being secured to a respective web member adapted to move in a fixed path relative to the adjacent fixed yarn-contacting bars, means to rotate said web member during rotation of said reel shaft, means eccentrically mounting the web members to normally position the yarn-contacting members carried thereby in a zone constituting one-half of the periphery of the reel in radially expanded position and the yarn-contacting bars carried thereby in a zone constituting approxi-
